UNITED STATES PATENT OFFICE.

SALVATORE STELLA, OF BROOKLYN, NEW YORK.

HEEL-SEAT-SHAPING MACHINE.

1,412,375.

Specification of Letters Patent. Patented Apr. 11, 1922.

Application filed April 19, 1920. Serial No. 374,839.

To all whom it may concern:

Be it known that I, SALVATORE STELLA, a subject of the King of Italy, residing at Brooklyn, in the county of Kings and State of New York, have invented new and useful 5 Improvements in Heel-Seat-Shaping Machines, of which the following is a specification.

This invention relates essentially to a machine for shaping the seat in a shoe to prepare it for receiving a wood heel which is usually glued to the shoe.

An object of the invention is to provide a presser die mounted on a plunger and made 10 to compress the rim portions of the sole so that the heel can be easily positioned at a saving of time and labor.

Another object of the invention is to provide means for adjusting the die to make it 15 fit shoes of different dimensions.

Another object of the invention is to provide a casing made to envelope the shoe, and a clamp having swinging jaws to engage the envelope, thus holding the shoe in a 20 fixed position while the die is in action.

The present invention is designed to be used in connection with the heel clamping machine described in the United States Patent No. 1,282,971, granted to me October 30 29th, 1918.

The invention resides more particularly in the novel combinations hereinafter described and claimed, reference being made to the accompanying drawing in which:

35 Fig. 1 represents a side elevation of a machine embodying this invention.

Fig. 2 is a rear view of the upper portion of the machine.

Fig. 3 is a vertical section of the plunger 40 die.

Fig. 4 is an inverted plan view of the same.

Fig. 5 is a perspective view of the shoe casing.

45 Fig. 6 is a detail side elevation showing the plunger slide retracted.

In the drawings the numeral 7 designates a base having front and rear columns 8 and 9 respectively supported on the base. A 50 shaft 10 projects upwardly from the front column. On the upper portion of the shaft is arranged a sleeve 11 having a bolt 12 coacting with a groove in the shaft. The bolt and groove connection prevent vertical 55 displacement of the sleeve relative to the shaft, but permits the sleeve to turn axially

on the shaft. A spring actuated pin 13 is arranged in a bore in the top of the sleeve and the upper end of the pin serves to mount thereon or centre a last 14 carrying a shoe 15 best seen in Fig. 1.

At the lower portion of the sleeve is pivoted a bifurcated lever 16 having a brace 17 extending upwardly from the rear of the lever. To the upper end of the brace is secured a casing 18 made to sheath the side and rear portions of the shoe. The casing is practically U-shaped and is preferably made of flexible material such as leather to conform to the curvature of the shoe. A 65 link 19 connects the said lever to a strap 20 fixed to a coupling 21 which is loosely mounted on the shaft. The upward movement of the coupling is stopped by means of a collar 22 secured to the shaft, while the 70 lower portion of the coupling is supported on a coiled spring 23 mounted on the shaft between the top of the column 8 and the coupling. The coupling is connected at 24 to one end of a rod 25 the other end of the 75 latter being pivoted to the treadle 26 swingingly mounted on a pivot 27 fixed to the rear of the frame.

On the rear of the sleeve is swingingly fulcrumed at 28 a pair of clamping members having jaws 29 and tail portions 30 made to engage the lever 16 as indicated in Fig. 2. Springs 31 tend to open or spread the jaws and at the same force the tail portions outward to impinge on the lever. 80 When it is desired to hold the shoe in a fixed position the treadle 26 is pushed downward sliding the coupling to compress the spring 10 and swing the lever 16 downward. The movement of the lever is transmitted to 85 the tail ends of the clamp moving them toward each other and the jaws will grip the sides of the casing. The casing being flexible, it will adapt itself to the shape of the shoe and thus hold it in a fixed position 90 while it is operated on. The brace 17 serves to mount the casing over the top of the sleeve and the slight movement of the lever downward actuates the brace and positions the casing relative to the insertion of the 95 shoe.

A plunger consisting of a die 32 presses on the rim portions of the shoe when the machine is in action. The die is made of two sections as shown in Fig. 4, and each 100 section is equipped with a rack 33 engaged by a pinion 34 mounted on the lower end 105

of a shaft 35 extending upward. A thumb button 36 is secured to the upper end of the shaft and actuation of the button rotates the gear and operates the racks to expand or contract the two die sections. The button can be provided with a pointer to coact with degrees denoting the size of the shoe and marked on the annular flange 37 of a nut located below the button.

10 The nut is screwed on to the top of a sleeve 38 arranged about the shaft and an arm 39 is connected to the sleeve. A coiled spring 40 is mounted between a shoulder on the lower portion of the sleeve and the arm.

15 The spring normally presses the arm against the flange on the nut, but when the die is in contact with the shoe, it will compensate for any curve or convexity of the shoe. The die is consequently suitable for shaping right or

20 left shoes in which the shape varies. The arm slides in a bearing 41 and a spring 42 retracts the arm as indicated in Fig. 6, when the pressure is removed from the plunger. The stem of the bearing is guided in the

25 column 9, and a link 43 connects it to a treadle 44 pivoted to the fulcrum 27 at the rear of the column. A spring 45 restores the treadle to its normal position and elevates the die from the shoe. The downward

30 movement of the arm 39 compresses the spring 40 and forces the lower obtuse ends of the die into contact with the upper rim portions of the sole, so that any upward movement of the die while compressing the

35 leather is taken up by the spring and consequent injury to the leather is obviated. A rack 46 pivoted to the treadle and normally engaged by a dog 47 will lock the treadle when the plunger is in action.

40 The operation of the machine is as follows:

The shoe mounted on the last is placed on the pin 13 and the casing 18 is clamped to the shoe by pushing the treadle 26 downward. The plunger die is slid outward by the operator from the bearing 41 until it is in the proper position over the shoe. The treadle 44 is then pushed downward forcing the die on to the sole to bevel or convex the

45 rim and thus prepare it for positioning the heel. The dog holds the treadle in a fixed position while the die is in action, but when the dog is operated to disengage it from the teeth of the rack the die will be carried

up with the bearing 41 and automatically 55 slid backward by the compression of the spring. In order to examine the shoe without removing, it can be turned on its axis moving therewith the sleeve 11 its connections with the shoe and the coupling be- 60neath the sleeve. The die while it is out of action can be heated by a gas jet or otherwise.

I claim:

1. A heel seat shaping machine comprising a column for mounting a shoe, a sleeve arranged on the column, a casing made to envelope a portion of the shoe, jaws for clamping the casing, means connected to the sleeve for actuating the jaws, and a spring 70 pressed plunger die made to coact with the shoe.

2. A heel seat shaping machine comprising a column for mounting a shoe, a sleeve arranged on the column, a casing made to 75 envelope a portion of the shoe, jaws for clamping the casing, a lever connected to the sleeve for actuating the tails of the jaws, a brace carried by the lever for mounting the casing, and a spring pressed plunger 80 die made to coact with the shoe.

3. A heel seat shaping machine comprising a column for mounting the shoe, a sleeve arranged on the column, a casing made to 85 envelope a portion of the shoe, jaws for clamping the casing, a lever connected to the sleeve for actuating the tails of the jaws, a brace carried by the lever for mounting the casing, a spring pressed plunger die made to coact with the shoe, and means for 90 sliding the plunger die backward out of alignment with the shoe.

4. A heel seat shaping machine comprising a column for mounting a shoe thereon, a spring pressed sectional plunger die made 95 to engage the shoe, means for actuating the plunger to elevate or lower the die, and means including a pinion and racks for adjusting the sections to expand or contract the die.

In testimony whereof I have hereunto set my hand in the presence of two subscribing witnesses.

SALVATORE STELLA.
